ALTERNATING CURRENT OPERATED NON-
INTERFERING SIGNALING SYSTEMManfred W. Muehler, Nutley, N. J., assignor to
American District Telegraph Company, Jersey
City, N. J., a corporation of New JerseyApplication July 13, 1934, Serial No. 734,931
Renewed April 26, 1939

21 Claims. (Cl. 177—360)

This invention relates to electric signal systems and transmitters and receivers therefor, and more particularly to systems wherein a large number of transmitters on the same circuit are prevented from interfering with each other, though it is noted that in some of the claims the invention is not limited to systems of the non-interfering type.

One object of the invention is to provide an improved system of this kind in which the transmitters are provided with motors operated from the central source of current at the receiving station, and wherein the motor is operated by alternating current while intermittent direct current signal impulses are superposed on the alternating current.

Other objects of the invention are to provide, in a system of this kind, improved signal means for indicating grounds and indicating line breaks and their removal.

Additional objects of the invention are to improve generally the simplicity and efficiency of such systems and apparatus and to provide an apparatus of this kind which are economical and reliable in operation, and economical to manufacture and install.

Still other objects of the invention will appear as the description proceeds; and while herein details of the invention are described in the specification and some of the claims, the invention is not limited to these, since many and various changes may be made without departing from the scope of the invention as claimed in the broader claims.

The inventive features for the accomplishment of these and other objects are shown herein in connection with a positive non-interfering successive signaling system, which briefly stated, includes a series of distant transmitters, each comprising an alternating current motor, and a coding switch operated by the motor.

The figure is a wiring diagram showing the system.

The system may be used for sending code signals from distant stations as on subscribers' premises, and receiving them at a central or other office.

The system

The system is here shown as comprising a series of any number of transmitters 5', 6, each comprising an induction or other self-starting alternating current motor 7, a cut-out cam 8, a change-over cam 9 and a code-wheel 10 carrying two different code signals, all operated by said motor. Each transmitter has a double-throw

shunt-switch 12 controlled by the cut-out cam.

A double throw signal-initiating or detector switch 15 associated with each transmitter at or near the transmitter or at a distance therefrom, is used to initiate the signals. The detector switch has a movable element 16 which may be operated by hand, or which may be connected to a valve, flow detector, thermometer or any hand or automatic device to be supervised, and moved from normal position in engagement with a normally engaged contact 17 to engage a normally disengaged contact 18. At the receiving or central station is located a coding relay winding 21 adapted to pass direct current and substantially preventing passage of alternating current and a condenser 22 and choke coil 23, in series, shunting said winding to pass alternating current. At the receiving station is also a detector relay including a solenoid 26, an armature 27, a normally engaged contact 28 and a normally disengaged contact 29. There is also a transformer including a primary 35 and a transformer secondary 36 in which is interposed a source 37 of direct current E. M. F. The main line circuit passes from one end 38 of said secondary through conductor 39, the receiver coding winding 21, or the condenser 22 and then as a detector loop 40 through each of said switches 12 and movable elements 16, to and through the break detector relay solenoid 26, said line circuit then continuing as a motor loop 41 passing in the same direction as the detector loop through a terminal of each motor-field coil 42, to the other end 43 of said secondary, whereby current may pass and the detector relay winding is held energized and the line is supervised.

The transmitter

A service line 45 in each transmitter is connected to the other end of the motor field coil 42 and through condenser 57 to the movable element 46 of a change-over double throw switch having its fixed contacts 47, 48 connected to said detector switch contacts 17, 18 respectively. The movable element 46 of the change-over switch is controlled by the inner land portion 50 of said change-over cam 9 to normally connect the service line with the normally disengaged detector switch contact 18 and before and during the first part of the code signal, and is controlled by the outer land portion 51 to connect the service line 50 to the other fixed contact 17 before and during the other part of the code signal. This permits the sending of a signal on the restoration to normal of the movable element 16, as will be explained.

5 The double throw shunt switch 12 in each transmitter is interposed in the detector loop adjacent to each detector, the elements 53, 54 normally maintain the continuity of loop 48 while 5 the element 55 connected to the service line is operated by said cut-out cam 8 to separate elements 53, 54 and break the detector loop and connect the left leg only of the loop 48 with the service line through elements 53, 55, thereby to 10 connect said service line with one end 38 of said secondary.

15 A condenser 57 is interposed in said service line 45 adjacent to the motor, whereby when the detector element 16 engages contact 18 alternating current may pass to the motor, without passing direct current, thereby energizing the motor field and opening a normally closed cut-out switch 58, 59 in the motor loop, opened by the armature 60 attracted by the motor field when 20 energized, to break motor loop 41 and leave the motor connected to the other end 43 only of said secondary, whereby all of the other transmitters are cut out and the break detector relay solenoid 26 is deenergized.

25 The condenser 22 and choke coil 23 in series around the coding solenoid allow alternating current to pass and the motor operates the transmitter and code wheel 10, intermittently closing a normally open code switch 62 shunting said 30 condenser 57 and engaged by the code teeth 121 to superpose direct current on the alternating current, which direct current may pass the receiver coding solenoid 21, as will be explained, and deliver code impulses to the receiver winding, thereby attracting the armature 63, closing switch 63, 64, and passing direct current through conductors 64, 65 from one terminal, of the direct current source to the other to operate the recording register 67.

35 Normally, when the transmitter is not operating, the supervisory current does not pass through the coding winding 21, but passes through a by-pass 70 in which is interposed a normally closed switch 71, 72 of a switching relay including a 40 winding 73 and the normally closed by-pass switch 71, 72, and ground switch 74, 75 and a normally open trouble switch 76, 77. Conductors 65, 79 connect one pole 80 of the direct current source with the armature 27 of the break detector relay; while conductors 81, 82, 66 connect the normally disengaged contact 29 of said relay through the switching relay winding 73 to the other pole 83 of said source, whereby when the detector relay 26 is deenergized, the by-pass switch 71, 72 is opened and the coding relay solenoid deshunted to cause the intermittent code signal current to pass through the winding 21 and actuate the register 67. The break indicating lamp 84 connected in parallel with the winding 73 lights whenever the solenoid 26 is deenergized.

The break detector

45 A trouble-bell relay 85, 86, 87 is provided for operating a trouble bell 88 and comprises a winding 85, adapted when energized to close a circuit through terminal 80, conductors 65, 88', 89, contact 87, armature 86, conductors 90, 66 and terminal 83. A double throw silencing switch comprises a normally disengaged contact 93 connected by a conductor 94 to the normally engaged contact 28 of the detector relay, a normally engaged fixed contact 95 connected by conductors 96, 97, 65 through said trouble switch 76, 77 to one pole 80 of said source 37, and a movable element 98 connected through conductor 99, resistor 100, conductor 101, trouble winding 85 and con-

ductors 90, 66 to the other pole 83 of said source, whereby when a break occurs anywhere in the main line 48, 41 and the relay 25 is deenergized, the relay winding 73 is energized, current passes through the trouble winding 85 and the bell 88 rings until the silencing switch movable element 98 is moved to the normally disengaged contact 93; and then when the break is mended and the break detector relay 25 energized and the switching relay winding 73 is deenergized, the trouble 10 relay winding is energized through conductors 65, 99, 100, 101, 90, 66 and the trouble bell is again sounded until the silencing switch element 98 is moved to original position, thus breaking the circuit through winding 85.

15

The ground detector

The ground detector includes a ground detector relay comprising an armature 104 connected through conductors 79, 65 to the terminal 80 of 20 said source 37, a normally engaged back contact 105, a normally disengaged front contact 106 and a solenoid 107 connected by conductors 109, 110 between the midpart of said source 37 and the element 15 of said ground switch, the other element 74 being grounded at the ground 112, whereby when a ground occurs on the line 40, 41 the ground detector winding 107 is energized and the normally disengaged contact 106 thereof is engaged by the armature 104.

30

A double-pole ground-signal silencing-switch comprises a normally open switch 114, 115 and a double throw switch 116, 117, 118, the latter switch having a normally engaged contact 116 connected by conductor 101 to the trouble relay 35 winding 85 and its movable element 117 connected through conductors 120, 121, through a ground lamp 122 to the normally disengaged ground detector contact 106, whereby when there is a ground and the contact 106 therefore engaged, 40 the trouble bell is sounded until the double throw switch is thrown from contact 116 to contact 118, thus breaking the circuit through conductor 101. The normally disengaged element 118 is connected by conductors 123, 66 to the pole 83 of the source 45 37, whereby the trouble lamp 122 continues to light, until the ground is repaired. The normally open switch 114, 115 is connected by conductors 125, 99 between the normally disengaged ground detector contact 104 and the trouble winding 85, and may, if desired, have its movable element 115 50 mechanically connected by the insulating bar 126 to the movable element 117 of the double-throw switch, whereby when the double throw switch is thrown to silence the ground bell, the trouble solenoid 85 is connected to the normally disengaged detector contact 106, thereby again to ring the bell when the ground is repaired, whereupon the silencing switch is thrown to normal and the lamp 122 and trouble solenoid 85 are deenergized.

55

It is noted that the lamp 122 lights whenever the winding 107 is energized because of ground; and that the lamp 84 lights whenever the solenoid 26 is deenergized by a line break. Thus, when the trouble bell sounds, these lamps indicate the kind of trouble.

60

Normal operation

The operation will be understood from the foregoing, and need now be only summarized as follows:

70

The system consists of a central station 20 for recording coded signals on the inking register 67 or similar recording device, and a double loop signaling circuit 40, 41 to which the various distant transmitters are connected.

75

In the diagram, the two loops 40 and 41 are shown, which extend through the premises or territory from where signals are to be received. The normal supervisory circuit can be traced as follows: From battery terminal 43 through one-half of the secondary 36 of the transformer, through loop 41 in which switches 58, 59 are connected in series, through the coil 26 of relay 25, through loop 40, in which switches 53, 54 are connected in series, then through switch 71, 72 of the switching relay, through the other half of the secondary of the transformer to terminal 33. Relay 25 is thus normally held energized, supervising the line.

Switch 15 is operated by the device, the condition of which is to be supervised, as, for instance, a valve, a pressure indicating device, etc. When the device changes its position, switch element 16 is thrown over to the right, for instance, closing a circuit from loop 40 through switch 46, 48, condenser 57, motor 1, to loop 41. Alternating current from the secondary windings 36 of the transformer will flow and start the motor. As the motor magnet becomes energized, the auxiliary armature 68 of the switch 53, 59 will be attracted, opening this switch. This shuts off the current for all transmitters and the loop 41 of such switch, whereby winding 26 is deenergized, thus energizing relay winding 73 through the back contact 29 of relay 25. This energizing of winding 73 opens the switch 71, 72 and inserts the coding relay winding 21 into loop 40. Thus the resistance of the winding 26 is removed as the resistance of winding 21 is inserted, maintaining the resistance of the line more nearly constant.

The winding 21 is shunted by the by-pass consisting of the condenser 22 or condenser 22 in series with the choke coil 23 and tuned to allow free passage for the alternating current. As soon as the motor starts to rotate, switch element 55 rides out of the notch 130 closing the switch 53, 55 and opening the switch 53, 54, thus shutting off the current for all motors more remote from terminal 33. As was explained, the motors more remote from terminal 43 were cut off by switch 53, 59. Other motors are thus prevented from running and sending in a signal at this time. The switch 53, 55 when thus closed connects the line 45 with the part of the loop to the left at element 16, thus allowing the motor to continue to run in case switch 16, 18 closes only momentarily.

As the code wheel 10 rotates, the coding switch 62 intermittently closes and shunts the condenser 57 according to the code to be transmitted. Every time this happens direct current will flow through loop 40, superimposing itself on the alternating current. However, the direct current will flow through the solenoid 21 instead of through the by-pass 22, 23. This relay will attract the armature 63 and operate the register 67 through its contact 64. After half a revolution of the code wheel shaft the first of the unlike code signals has been transmitted. Then the element 55 rides into the other notch 130' and the switch 53, 54 again closes. The outer land portion 56 of the cam 8 then also opens switch 46, 48 and closes switch 46, 47. If element 16 has been left on contact 18, current is thus cut off from the line 45 and relay 25 is reenergized. Other motors can now send in a signal in a similar manner. Switch 53, 59 has a lead in operation over switch 53, 54, so that if two or more transmitters are waiting to signal at the same time, the one nearest terminal 43 will always transmit before the others, thus making the operation successive.

If two switches 17 operated at exactly the same time, the transmitter nearest terminal 43 will operate first. Suppose the lower transmitter to be operating; its switches 54 and 58 would be open and no current from 43 could pass open switch 58 of this transmitter, and therefore no current from terminal 43 could reach any other transmitter and no transmitter could operate. Suppose the upper right hand transmitter to be operating; its switches 54 and 58 would open; no current from 33, 39 could pass open switch 54 to reach and operate the other transmitters. Consider that the middle transmitter is operating and that the switches 15 of the two end transmitters are turned to start such end transmitters operating as soon as the middle transmitter ceased operating and closed its switches 54 and 58. The instant these middle-transmitter switches closed, both end-transmitter switches 58 (being connected in multiple) would open or tend to open simultaneously immediately because they are operated by the motor field; but neither of the switches 54 would open immediately, because it can open only after the cam 8 has made a considerable movement. Thus switch 58 has what is called a lead in operation over the switch 54. Thus both end-transmitter switches 58 would open or tend to open first (before switch 54); and when this took place, the switch 58 of the lower transmitter would open and prevent current from terminal 43 from passing to the other transmitters, and only the transmitter nearest 43 would operate. If for some reason switch 58 of the upper right end transmitter should open first, it would not prevent current 43 from reaching the right end transmitter, whereupon 58 at lower end would open and cut off the upper transmitter from terminal 43 before the upper end transmitter switch 54 could open and cut off the lower end transmitter from terminal 33.

If the element 16 remains on contact 18, the second part of the code signal is not sent, but if the element 16 should be thrown back to its original position on contact 18, a new starting circuit will be established through the now closed switch 46, 47. The motor will again start as before and send the second part of the signal in the same way as before, the coding being controlled by the second half 12' of the code wheel, making the signal distinctive, from the one sent before from the half 11', in order to indicate the position of switch element 16. After completing the second half of the revolution, all cams will be in normal position again as shown in the drawing.

Operation of the ground detector

Upon occurrence of a ground on one of the two line loops 40 or 41, current will pass from battery through conductors 109, 110, relay 107, switch 75, 74 and ground 112, and ground detector relay armature 104 will close on its front contact 106 and energize a circuit through conductor 121, the ground lamp 122, the left movable element 117 of the associated silencing switch, and the coil 86 of the trouble relay, energizing this relay. This relay then energizes the trouble bell through its contacts 86, 87, calling the attention of the operator to the ground condition. The operator can silence the bell by throwing the silencing switch elements 115, 117 to the left, thus breaking the circuit through coil 86 by opening the switch 116, 117. The light, however, will not be extinguished until the ground trouble has been removed, since current will then pass through contact 118 and conductors 123, 86. If the 75

ground is removed and the magnet 107 energized, when the switch elements 115, 117 are thus thrown to the left, the relay coil 85 will be energized through conductors 66, 90, the series resistor 100, conductor 99, the right hand element 115 of the silencing switch, contact 114 and the back contact 105 of the ground relay. The bell will then ring again, when the ground is removed, and remind the operator to throw the silencing switch back to the normal position of the drawing.

A single ground on the line circuit 40, 41 will, however, not prevent the transmission of a regular code signal, since relay coil 73, when energized during signaling as explained, opens its ground switch 74, 75, disconnecting the regular ground 112 from the system. There will now only remain the trouble ground on the line, which will have no effect.

Operation of the break detector

If a break happens in the line 40, 41, the break detecting relay 25 is deenergized, thus energizing switching relay coil 73 and the break-indicating lamp 84 in parallel therewith through the back contact 29. Trouble relay coil 85 is thus energized through its series resistor 100, conductor 99, switch 98, 95, conductor 96, relay switch 76, 77 and conductors 97, 65. The trouble bell can be silenced by throwing the associated silencing switch element 98 to the left, while the break-indicating signal lamp 84 will remain lighted until the break has been cleared. When the break is cleared the relay 25 is energized causing current to pass through the trouble relay coil 85, the series resistor 100, the silencing switch 98, 93, and the contact 28 of relay 25, thus reminding the operator to throw the silencing switch element 98 back to its normal position shown in the drawing.

It will be noticed that a break in either of the two line wires will only prevent those transmitters from sending in a signal which are located on that side of the break where the supervisory relay 25 is connected. For instance, if the loop 40 be broken at some point between the detector switches 15, the part of this loop to the left of the break will be still connected to the terminal 38, and the transmitter 5 may operate as previously described. But the part of the loop 40 to the right of such break will not be connected to the terminal 38 at all, and the transmitter 6 cannot operate.

Whenever the bell 88 rings as a result of a break or a ground, the lamp 84 or 122 will indicate whether the defect is a break or a ground.

I claim as my invention:

1. In combination, a series of code impulse transmitters; a coding receiver; a break detector relay; a source of direct current; a main line passing as one loop from one pole of said source adjacent to said transmitters and then through the detector relay winding, said line then continuing as a second loop in the same direction past said transmitters through the coding receiver to the other terminal of said source; a normally closed shunt shunting the coding receiver; means for connecting each transmitter between adjacent parts of the respective loops; means associated with each transmitter to break the loops respectively on respective opposite sides of such transmitter to leave only such transmitter connected in a circuit between opposite poles of said source thereby to deenergize the detector relay; and

means operated by the detector relay when deenergized to break said normally closed shunt.

2. In combination, a transmitter comprising an alternating current motor, and a coding switch operated by the motor; a coding receiver; a condenser shunting said receiver; a source of direct current; a conductor passing from one end of said source; to said condenser and thence to said transmitter; a second conductor passing from said transmitter to the other end of said source; means for connecting the coding switch and motor in series between the respective conductors; a condenser in the transmitter shunting the coding switch; and means to superpose alternating current E. M. F. on the direct current E. M. F. 10

3. In combination, a line; a condenser therein; a code switch shunting the condenser; and an alternating current motor in series with the coding switch operable by alternating current in the line for operating said switch. 20

4. In combination, a series of transmitters; a coding receiver; a resistance; a source of direct current; a main line passing as one loop from one terminal of said source through said transmitters and then through said resistance, and then continuing as a second loop through said transmitters to the other terminal of said source; means for connecting each transmitter between adjacent parts of the respective loops and removing said resistance from the line and simultaneously inserting said receiver. 30

5. In combination a pair of parallel lines, transmitters bridged therebetween and having code means adapted to make and break the bridge connection between said lines; and means operated by each transmitter for breaking one line at one side of each transmitter and the other line on the other side of such transmitter. 35

6. In combination, a series of code impulse transmitters; a coding receiver; a detector relay; a source of current including elements in series; a main line passing from one terminal of said source through said coding receiver, said transmitters and the detector relay winding to the other terminal of said source, to form a transmitting circuit and adapted to operate the detector relay during transmitting; a ground detector relay comprising a winding connected between a ground and the connection between said elements; to cause the ground relay when energized to energize the trouble alarm means; and means operated by the detector relay during transmitting to remove said ground. 50

7. In combination, a pair of line loops; a series of transmitters, each transmitter including a service line connected between said loops; a motor in each transmitter started by current in the service line; a make and break code means, and a detector switch interposed in the service line; the motor operating the code means; the detector switch being operable to cause said current to start the motor; and means operated by the motor to break the loops on respectively one loop on one side of said line and the other loop on the other side of said line and to disconnect the motor service line from said detector switch. 55

8. In combination, a condenser; a code switch shunting the condenser; and a motor in series with the code switch operable by pulsating current for operating the code switch. 70

9. In combination, a series of transmitters; a coding receiver; a D. C. source; a source of A. C. E. M. F. superposed on said D. C. source; a loop passing from one pole of said source adjacent to said transmitters; and a second loop passing 75

in the same direction past said transmitters through the coding receiver to the other terminal of said source; each transmitter including a bridging means for at times connecting adjacent portions of the respective loops, a code switch and an A. C. motor therefor interposed in series in said bridging means, a condenser shunting the code switch, and means operated by each motor, when its bridging means is connected, to break the loops respectively each on the side of the bridging means most remote from the source to leave only one code switch connected to the receiver, and only the motor of such switch connected to the A. C. source.

10. In combination, a series of transmitters; a coding receiver; a source of current; a main line passing as one loop from one terminal of said source through said transmitters in one direction and then continuing in said direction as a second loop through said transmitters and the receiver to the other terminal of said source; bridging means in each transmitter adapted to be connected between adjacent parts of the respective loops; a coding means in each bridging means for varying current therein; and a motor in each bridging means to operate the coding means while the bridging means is connected.

11. In a combination as in claim 10, means operated by each motor during operation for breaking the loops each at the side of the associated bridging means most remote from the source, thereby to isolate the non-transmitting stations from the system while the transmitting station transmits.

12. In combination, a series of code impulse transmitters; a coding receiver; a detector relay; a source of current comprising elements connected in series; a main line passing as one loop adjacent to said transmitters and along the series in one direction from one pole of said source and then through the detector relay winding, said line then continuing as a second loop in the same direction past said series of transmitters through the coding receiver to the other terminal of said source; means for connecting each transmitter between adjacent parts of the respective loops during transmitting, thereby to short out and deenergize the detector relay winding; a ground detector connected to a part of said source between said elements and having a ground to conduct current when the line is grounded, to operate the ground detector; and means operated by the detector relay when deenergized for removing said ground thereby to allow any operated transmitter to transmit to the receiver.

13. In combination, a series of code impulse transmitters; a coding receiver; a break detector relay; a source of current comprising elements connected in series; a main line passing as one loop adjacent to said transmitters from one pole of said source and then through the detector relay winding, said line then continuing as a second loop in the same direction past said transmitters through the coding receiver to the other terminal of said source; bridging means for connecting each transmitter between adjacent parts of the respective loops; means associated with each transmitter to break the loops respectively each at the side of such bridging means most remote from said source, thereby to deenergize the detector relay; a ground detector connected to said source between said elements and having a ground to conduct current when the line is grounded, to operate the ground detector; and

means operated by the break detector relay when deenergized for removing said ground.

14. In combination, a line; a coding means in said line operable to intermittently vary direct current in said line; pulsating motor means operable by pulsating current superposed in said line for operating said coding means; and means for allowing the pulsating current to pass the coding means while preventing the passage of direct current.

15. In combination, a line; a coding means in said line adapted to intermittently vary direct current in said line; a receiver operated by direct current in said line; an alternating current motor means in series with the coding means and operated by alternating current in said line for operating said coding means; and a condenser shunting the coding means.

16. In combination, a line; a coding means in said line operable to intermittently vary direct current in said line; pulsating motor means operable by pulsating current superposed in said line for operating the coding means.

17. In combination, a line; a coding means adapted to intermittently vary direct current in said line at the coding means; a receiver remote from the coding means operated by direct current in said line; an alternating current motor means operated by alternating current in said line for operating said coding means.

18. In combination, a normally closed circuit including therein a battery and a coding receiver; a plurality of transmitters; a ground detector connected to the mid part of said battery and having a ground to conduct current when the line is grounded to operate the ground detector; a normally energized detector relay in said circuit; and means operated by the detector relay when deenergized to remove said ground detector from the circuit; said circuit comprising a line passing as one loop from one terminal of the battery through said transmitters, then through the relay winding and as a second loop through said transmitters to the other terminal of the battery; a bridging means with a code switch therein in the associated transmitter adapted to be connected to adjacent parts of the respective loops during signalling; the arrangement of said circuit being such that a bridging means when connected cooperates with said circuit to bring about the function of shorting out said relay, thereby to remove the ground only while the bridging means is connected thereby to allow transmitting, when a line is grounded, from any operating transmitter to the receiver.

19. In combination, a circuit having a source of current; a ground detector interposed between the circuit and a ground; transmitters and a receiver so connected to the circuit that operation of any transmitter operates the receiver, during accidental grounding if said ground is removed; and means influenced by operation of a transmitter for removing said ground.

20. In combination, a circuit including therein a source including elements in series, and a receiver; a series of transmitters each having a means adapted to cause current variations in the receiver current when the transmitter operates; a ground detector connected to said circuit between said elements and having a ground to conduct current when the line is grounded to operate the ground detector; a detector relay in said circuit influenced to operate by circuit current change during transmitting; and means operated

by the detector relay when deenergized to remove said ground from the circuit.

21. In combination, a normally closed circuit including therein a receiver, and a source of current consisting of elements in series; a series of transmitters each having a coding means adapted to be connected in the circuit and to cause code current variations in the receiver current when the transmitter operates; a ground detector connected to said circuit between said elements and having a ground to conduct current when the line is grounded, thereby to operate the ground detector; a normally energized relay in said circuit; means operated by the relay when

deenergized to remove said ground from the circuit; said circuit comprising a line passing as one loop from one terminal of the battery through said series of transmitters in one direction of the series, then through the relay winding and then as a second loop through said transmitters to the other terminal of the battery; each transmitter including a bridging means in the associated transmitter adapted during transmitting to connect adjacent parts of the respective loops, thereby shorting out said relay, thereby to deenergize the relay and remove the ground during transmitting.

MANFRED W. MUEHTER.
